COVER PLATE FOR A SEWING MACHINE FRAME

Edward L. Koenig, Westport, and Raymond J. Evans, Fairfield, Conn., assignors to The Singer Manufacturing Company, Elizabeth, N. J., a corporation of New Jersey

Application December 13, 1955, Serial No. 39,307

Term of patent 14 years

(Cl. D70—2)

Fig. 1

Fig. 6

Fig. 2

Fig. 4

Fig. 5

Fig. 3

Fig. 7

Fig. 1 is a perspective view of a cover plate for a sewing machine frame embodying our new design;

Fig. 2 is an elevational view of the exposed or outside of the cover plate;

Fig. 3 is an elevational view of the inside surface of the cover plate;

Fig. 4 represents a vertical cross section of the cover plate taken substantially along line 4—4 of Fig. 2;

Fig. 5 represents a side elevation taken from the left hand side of Fig. 2;

Fig. 6 represents a top plan view of the cover plate; and

Fig. 7 represents a bottom plan view of the cover plate.

The dotted line showing of the sewing machine in Fig. 1 is for illustrative purposes only.

What we claim herein is:

The ornamental design for a cover plate for a sewing machine frame, as shown and described.
